UNITED STATES PATENT OFFICE.

GUY M. GEST, OF CINCINNATI, OHIO.

MANHOLE-TERMINAL FOR CONDUIT-SECTIONS.

SPECIFICATION forming part of Letters Patent No. 774,318, dated November 8, 1904.

Application filed July 12, 1902. Serial No. 115,312. (No model.)

To all whom it may concern:

Be it known that I, GUY M. GEST, a citizen of the United States, residing at Cincinnati, in the county of Hamilton and State of Ohio, have 5 invented certain new and useful Improvements in Manhole-Terminals for Conduit-Sections, of which the following is a specification.

This invention relates to manhole-terminals for conduit-sections; and its object is to provide 10 means for connecting a terminal section of a conduit for electric conductors with a manhole structure.

In connecting terminal conduit-sections with manhole structures it is desirable to provide 15 rounded surfaces at the point of juncture of the section with the walls of the manhole-chamber to avoid abrupt bends in the conductors contained within the conduit. In laying the conduits it sometimes occurs that an 20 end section of a length regularly manufactured may not be of the exact length required to properly finish a terminal at the wall of a manhole-chamber, and it is therefore desirable that means be provided to avoid the necessity 25 of cutting terminal sections in order to effect a result such as described.

With the before-mentioned objects in view my invention consists of a frame preferably of vitrified material, adapted to surround the 30 end of the terminal section and to be slid longitudinally of the latter at or near its point of connection with the manhole-chamber, having its end thereof adjacent to the wall of the manhole so formed as to present curved 35 surfaces over which the conductors are adapted to extend.

The invention will be more specifically described in connection with the accompanying drawings, which form part of the specification, and its novel features will be defined in the appended claims.

In the drawings, Figure 1 is a view in perspective of a manhole-terminal connection embodying the invention. Fig. 2 is a section of 45 the same on the line 2-2 of Fig. 1, and Fig. 3 is a perspective view of a modified embodiment of the invention.

Corresponding parts in all the figures are denoted by the same reference characters.

50 The reference-numeral 1 designates a frame

adapted to surround and to occupy various positions longitudinally of the conduit-sections, said sections being preferably made of vitrified material and preferably of the rectangular form shown. The end of the section which 55 is adapted to be secured within the manhole structure has the corners 2, formed by its end face and its inner walls, curved outwardly to present smooth inclined surfaces, and thus avoid the possibility of thereby forming 60 abrupt bends in the conductors where the latter may contact the frames 1.

In the form shown in Figs. 1 and 2 a single conduit-section 3 is employed with the frame 1 and may be solid, as shown in Fig. 1, or, 65 as shown in Fig. 3, the frame may be built up of sections, as shown by dotted lines, instead of being molded in a single piece and may inclose one conduit-section, as shown in Fig. 1, or a plurality thereof, as shown in 70 Fig. 3.

The utility of the invention will be readily appreciated, as it affords effective means for connecting terminal conduit-sections to a manhole structure, and by manufacturing the 75 frames in standard sizes with reference to the conduit-sections commonly employed the labor and time required for connecting the terminal sections may be materially reduced.

While the rectangular form of frame shown 80 in the drawings is entirely practicable and probably the best embodiment of the invention, I would have it understood that I reserve the right to make all such changes in construction as may be included within the 85 purview of the following claims.

Having thus described my invention, I claim and desire to secure by Letters Patent—

1. In a conduit for electrical conductors, the combination with a hollow conduit-section, of 90 a hollow frame removably located thereon surrounding and projecting beyond one end of said section its exterior surface being straight from end to end and its interior surface at one end being beveled, substantially 95 as described.

2. In a conduit for electrical conductors, the combination with a hollow conduit-section, of 100 a hollow rectangular frame removably located thereon surrounding and projecting beyond

one end of said section its exterior surface being straight from end to end and its interior surface at one end being beveled, substantially as described.

5 3. In a conduit for electrical conductors, the combination with hollow conduit - sections grouped together, of a hollow sectional frame surrounding one end of said conduit-sections its exterior surface being straight from end to end and the interior surface at one end being beveled, substantially as described.

10 4. In a conduit for electrical conductors, the

combination with hollow conduit - sections grouped together, of a hollow sectional frame surrounding one end of said conduit-sections its exterior surface being straight from end to end and the interior surface at one end being beveled, substantially as described. 15

In testimony whereof I have signed my name in the presence of the subscribing witnesses. 20

GUY M. GEST.
